LOAD EQUALIZER FOR PUMPS

Howard C. Robinson, Pine City, Minn.

Application June 16, 1933, Serial No. 676,120

7 Claims. (Cl. 103—206)

My invention relates to load equalizers for pumps and similar devices and has for its object to provide an equalizer adapted to be utilized in conjunction with a pump operated through a windmill, and particularly windmills having a tower constructed with angle uprights and a pump rod reciprocable vertically within the confines of the uprights.

An object of the invention resides in providing a load equalizer capable of being easily and readily attached to the parts of a windmill without alteration or reconstruction thereof.

Another object of the invention resides in constructing the load equalizer with a support adapted to be secured to one of the uprights of the windmill tower and particularly to such types of windmills as utilize angles in the construction of the uprights of the tower.

An object of the invention resides in constructing the equalizer with an arm pivoted to said support and extending diagonally across the windmill tower toward the pump rod thereof.

Another object of the invention resides in employing a compression coil spring acting between the arm and the support, said coil spring being adapted to be compressed during the down stroke of the pump rod to store energy therein and being further adapted to impart the stored energy to the pump rod on the upstroke thereof.

A feature of the invention resides in the specific construction of the clamp by means of which the end of the arm is pivoted to the pump rod.

An object of the invention resides in the specific construction of the support and its manner of attachment to the upright of the windmill.

A still further object of the invention resides in the specific construction of the mechanism by means of which the spring utilized to store energy is compressed.

Other objects of the invention reside in the novel combination and arrangement of parts and in the details of construction hereinafter illustrated and/or described.

In the drawing:

Fig. 1 is a plan sectional view of a portion of a windmill tower illustrating the application of an embodiment of my invention thereto.

Fig. 2 is a fragmentary elevational view taken on line 2—2 of Fig. 1.

Fig. 3 is an elevational sectional view taken on line 3—3 of Fig. 1 and drawn to a larger scale.

Fig. 4 is a side elevational view of the load equalizer detached from the windmill.

Where power for operating pumps is procured

from windmills, it frequently occurs that unless a stiff wind is blowing the windmill will be stopped before the pump rod reaches the top of its lifting stroke. In numerous such cases, however, the windmill operates quite freely during the return stroke of the pump rod. The present invention provides a simple and practical device which may be readily attached to existing windmill structures and by means of which the power developed by the windmill during the down stroke of the pump rod may be utilized to assist in raising the pump rod during the lifting or upstroke thereof.

For the purpose of illustrating my invention I have shown a portion of a windmill tower which is indicated in its entirety at A. This tower consists of uprights 10, 11, 12 and 13 which are arranged in inclined relation and which are secured together at suitable intervals through cross frame members 14, 15, 16 and 17. The uprights 10, 11, 12 and 13 are braced through braces 18 and 19 which cross one another and are secured to said uprights in the usual manner. In the construction of windmill towers the usual practice is to employ angles for the uprights 10, 11, 12 and 13 as well as for the cross members 14, 15, 16 and 17, which parts are riveted or bolted together as desired. The braces 18 and 19 may likewise be constructed of angles or the same may be formed of bar material as shown in the drawing. At the center of the windmill tower A is provided the usual pump rod 20 which is centrally disposed with respect to the uprights 10, 11, 12 and 13 and is located within the confines thereof. The pump rod 20 is connected to the pump and to the crank on the head shaft of the windmill and is operated in the usual manner to cause vertical reciprocation thereof. Inasmuch as windmill construction is well known in the art and forms no particular feature of the invention, a complete windmill has not been illustrated.

My invention proper comprises a support 21 which is attached to one of the uprights of the windmill tower. In the drawing, the same has been illustrated as attached to the upright 11. This support includes an angular portion 22 adapted to fit into the reentrant angle of the upright 11. This angular portion is constructed with flanges 23 and 24 which issue outwardly therefrom and which project outwardly beyond the edges of the legs 25 and 26 of upright 11. The support 21 is held attached to the upright 11 through two V-bolts 27 and 28 which are constructed with angular portions 29 adapted to fit about the salient angles of the upright 11 and which are con-

structed with threaded shanks 30 adapted to extend through the flanges 23 and 24 of the support 21. Nuts 31 threaded upon the shanks 30 serve to draw the angular portion 22 of the support 21 against the upright 11 and to hold the said support rigidly attached to said upright.

At the lower end of the angular portion 22 of support 21 are provided two ears 32 and 33 which extend outwardly therefrom in spaced relation 10 and toward the pump rod 20. Between these two ears is disposed one end of an arm 34 constructed of bar material which arm is pivoted to said ears through a pin 35 which passes jointly through both of said ears and said arm. This 15 pin is held in position with respect to the said ears through suitable cotter keys 36 which pass through the ends of said pin. The arm 34 extends diagonally of the tower A toward the pump rod 20 and is pivotally connected at its outer 20 end to a clamp mechanism 37 which will now be described in detail.

The clamp mechanism 37 comprises a jaw member 38 which is formed with a V-shaped groove 39 extending longitudinally of said jaw member. A complementary jaw member 40 is also utilized which similar to the jaw member 38 is constructed with a V-shaped groove 41. The two jaw members 38 and 40 are adapted to fit on opposite sides of the pump rod 28, the diagonally 30 opposite corners of said pump rod fitting into the respective grooves 39 and 41 of said jaw members. The two jaw members are provided with flanges 42 and 43 which issue outwardly from the said jaw members and which overlie one another. 35 Bolts 44 passing through said flanges serve to draw the jaw members toward one another and to clamp the clamp mechanism securely in place upon the pump rod 20 of the windmill. The jaw member 38 is constructed with two ears 45 and 40 46 which issue outwardly therefrom in spaced relation and toward the support 21. The outer end of the arm 34 is disposed between these ears and is pivoted thereto through a pin 47 which extends jointly through said ears and arm. Cotter keys 48 passing through the ends of this pin hold the same in position. By means of this construction the pump rod 20 may raise and lower and during the movement thereof the arm 34 is moved from the two extreme positions shown 50 in full and dotted lines in Fig. 2. In the construction of windmills the guides which guide the pump rod 20 are spaced a considerable distance apart. In the installation of the load equalizer, the same is preferably situated at some location 55 intermediate the guides so that the pump rod 20 may shift laterally a small amount to compensate for the movement of the free end of the arm 34 in the arc of a circle. To further compensate for such movement the openings through 60 which the pins 35 and 47 extend are made sufficiently loose so that some longitudinal movement of the arm 34 may be had thereby.

At the upper part of the support 21 is provided a bracket 49 which projects outwardly therefrom and extends toward the pump rod 20. This bracket is constructed with a shelf portion 50 which is spaced from the arm 34 and overlies the same. A rib 51 formed on the bracket 49 connects the shelf 50 with the angular portion 22 of support 21 and stiffens and reinforces the same. Extending through the shelf 50 of bracket 49 is a link 52 which may be constructed of a round rod which is slidably guided for movement through an opening 53 in said shelf. This link is constructed at its lower end with a hook or eye 54

which is adapted to hook into a hole 55 in the arm 34 immediately below the hole 53 in shelf 50. The upper end 56 of link 52 is threaded to receive a nut 57 and a lock nut 58. A large washer 59 is placed upon the link 52 and is disposed adjacent the nut 57. Encircling the portion of the link 52 which extends outwardly from the shelf 50 of bracket 49 is a compression coil spring 60. This spring is seated at its lower end against the link 52 and at its upper end against the washer 59. 10 By means of the nuts 57 and 58 the tension on the spring 60 may be adjusted to meet with the desired requirements.

My invention is installed on a windmill in the following manner. The load equalizer may be 15 attached to the pump rod 20 at any locality with respect to the length thereof. Inasmuch as the uprights of the windmill tower gradually come closer to the pump rod 20 near the upper end of the tower it can readily be comprehended that a 20 single length of operating arm can be employed. In installing the device the particular height of the tower is first determined at which the distance from the pump rod to the uprights corresponds to the dimensions of the equalizer. The 25 support 21 is next placed at such locality within the reentrant angle of the particular upright on which the same is to be mounted and the two V-bolts 27 and 28 applied about the salient angle of the upright and the shanks thereof inserted 30 through the proper holes in the flanges 24 of said support. Nuts 31 are next loosely applied. The clamp 37 is then placed about the pump rod and the bolts 44 inserted through the holes in the flanges 42 and 43 of said clamp; these bolts also 35 being loosely applied to the clamping device. It will be readily comprehended that considerable lateral play is possible with the pump rod so that the parts are easily brought together. The pump rod is then raised to its uppermost position. The 40 arm 34 is normally in the position shown in dotted lines in Fig. 2 which position corresponds with the uppermost position of the pump rod. The entire equalizer is now raised or lowered, as the case may be, until a slight lateral movement of 45 the pump rod toward the upright is procured. The various bolts are then tightened down which securely attaches the support 21 to the upright and the clamping device 37 to the pump rod. The device is now ready for use.

The operation of the load equalizer is as follows: When the arm 34 is at its uppermost position very little tension is given to the spring 60. As the pump rod lowers arm 34 is swung downwardly which causes the link 52 to be drawn 55 downwardly, the said link being pivoted to arm 34 through the eye 54 and the hole 55 in said arm and sliding through the hole 53 and shelf 50 of bracket 49. This causes the spring 60 to be compressed and the energy required to compress it to 60 be stored therein. When the pump rod starts on its upstroke, which is the lifting stroke of the pump, the energy stored in spring 60 is freed and delivered to the pump rod through the arm 34. This causes the power required by the windmill 65 to operate the pump rod to be greatly reduced whereby less wind is required to operate the pump than would otherwise become necessary. By means of this construction the power developed by the windmill is more uniformly applied, 70 thereby requiring less force than would otherwise be necessary. The amount of energy stored can to a certain degree be adjusted through adjustment of the nut 57 and lock nut 58. In this manner substantially uniform action can be had 75

and a smooth and easy operation of the pump procured.

My invention is highly advantageous in that an extremely simple and practical device is provided whereby the load on a windmill may be equalized so as to permit of pumping water uniformly and so as to cause the windmill to travel at a substantially uniform speed. With my invention water can be pumped with considerably less wind pressure than would be required without the use of the invention. The device is extremely simple in construction and has no complicated parts to get out of order. The tension of the spring and the amount of energy stored can be adjusted to meet with the requirements. The device is easily attached to existing windmill structures without alteration or reconstruction thereof. No complicated tools or apparatus are required in mounting the device on a windmill. Due to the manner of attaching the device to the windmill no adjustment of the length of the arm need be made. My invention can be constructed at a reasonable cost and by means and apparatus readily available.

Changes in the specific form of my invention, as herein disclosed, may be made within the scope of what is claimed without departing from the spirit of my invention.

Having described my invention, what I claim as new and desire to protect by Letters Patent is.

I claim:

1. An equalizer for use, a tower including a plurality of uprights, constructed of angles, one of said uprights being arranged with its reentrant angle facing inwardly of the tower and a vertically reciprocable rod disposed within the confines of said uprights, said equalizer comprising a support having an angular portion fitting within the reentrant angle of the specifically referred to upright, and extending outwardly beyond the edges of said upright and a V-bolt fitting said upright about the salient angle thereof and extending through the outwardly projecting portions of said support, an arm pivoted to said support and extending from said support toward said rod, means for pivoting said arm to said rod and a spring acting between said arm and support.

2. A load equalizer comprising a support, an arm pivoted to said support and extending outwardly therefrom, a member formed on said support and issuing outwardly therefrom in the same direction as said arm, said member being disposed in overlying relation with respect to said arm, a link pivoted to said arm and extending through said member, and a spring encircling said link and acting between said member and the end of said link and a reciprocating member connected to said arm.

3. An equalizer for use with a windmill having a tower including a plurality of uprights and a vertically reciprocable rod disposed within the confines of said uprights, said equalizer comprising a support, means for attaching said support to one of the uprights of the tower, an arm pivoted to said support and extending toward the rod, means for pivotally connecting said arm with the rod, a bracket formed on said support and extending outwardly therefrom in the same

direction as said arm and spaced from said arm, a link pivoted to said arm and extending through said bracket, and a compression coil spring encircling said link and acting between said bracket and the end of said link.

4. An equalizer for use with a windmill having a tower including a plurality of uprights, constructed of angles, one of said uprights being arranged with its reentrant angle facing inwardly of the tower and a vertically reciprocable rod disposed within the confines of said uprights, said equalizer comprising a support having an angular portion fitting within the reentrant angle of the specifically referred to upright, a clamp for holding said support attached to said upright, an ear issuing outwardly from said support at the lowermost portion thereof, an arm pivoted to said ear and extending from said support toward said rod, a bracket issuing outwardly from said support above said ear and spaced therefrom, a link pivoted to said arm and extending through said bracket, and a compression coil spring encircling said link and acting between said bracket and the end of said link.

5. An equalizer for use with a windmill having a tower including a plurality of uprights and vertically reciprocable rod disposed within the confines of said uprights, said equalizer comprising a support, means for attaching said support to one of the uprights of the tower, an arm pivoted to said support and extending toward the rod, means for pivotally connecting said arm with the rod, a bracket extending outwardly from said support in the same direction as said arm and spaced from said arm, said arm having an opening therein, and a link passing through said bracket, said link being formed with an eye received within the opening of said arm, and a compression coil spring encircling said link and acting between said bracket and the end of said link.

6. A load equalizer for use with a vertically reciprocable rod of square cross section and a tower including four uprights symmetrically disposed with respect to said rod, said equalizer comprising a support, means for attaching said support to one of said uprights, an arm pivoted to said support and extending diagonally across the tower toward said rod, a pair of plates extending transversely of said arm and having V-shaped grooves for the reception of opposite corners of the rod, means for clamping said plates together, an ear issuing outwardly from the plate nearest said arm, said ear being disposed near the center of said plate, means for pivoting said arm to said ear, and a spring acting between said arm and support.

7. An equalizer for use with a windmill having a vertically reciprocable rod and a tower provided with uprights, said equalizer comprising a single support attached to one of said uprights, an arm pivoted to said support and connected to said rod, a member extending outwardly from said support in the same direction as said arm and spaced therefrom, a spring seated at one end against said member and extending in a direction away from said arm, and means for connecting the outer end of the spring with said arm.

HOWARD C. ROBINSON.
